UNITED STATES PATENT OFFICE.

WILKIE HORATIO HOLTBY, OF CHICKASHA, OKLAHOMA.

BELT-DRIVEN PACKER.

Application filed June 13, 1925. Serial No. 36,890.

- This invention relates to an automatic attachment for belt driven packers. The present invention partakes of the nature of an improvement or adaptation of my prior 5 Patent No. 1,443,023, granted Jan. 23, 1923. This patent has for its subject-matter an automatic attachment for steam driven packers, and while the present invention utilizes some of the instrumentalities shown 10 and described in the patent this invention presents a new organization which is adapted for use as an automatic attachment for belt driven packers as distinguished from steam driven packers.
- 15 The object of the invention is to provide an attachment of this character which automatically operates to cause the trumper head to descend when the press box is full of cotton and to cause the trumper head to remain stationary at the upper limit of its return movement for an interval sufficient to permit the refilling of the press box.
- 20 A further object resides in the provision of an attachment of this character which is 25 of simple and durable construction, reliable and effective in operation and easily and comparatively inexpensively manufactured.
- Other objects and advantages reside in 30 certain novel features of the construction, arrangement and combination of parts which will be hereinafter more fully described and particularly pointed out in the appended claims, reference being had to the 35 accompanying drawings forming a part of this specification, and in which:
- Figure 1 is a fragmentary perspective view illustrating an automatic attachment constructed in accordance with the present invention, and
- 40 Figure 2 is a view thereof partly in transverse vertical section and partly in end elevation.
- Referring to the drawings it will be seen 45 that the invention will be shown as applied to a cotton packer of the type known in the art as the Cameron cotton packer. It is to be understood at this point that this invention may be used on Murray, Dixie and 50 Continental packers as well as on the Cameron packer, the Cameron packer being selected merely for the purpose of illustration.
- Referring to the drawings, the numeral 1 55 designates the press box to which cotton is fed by an automatic rake 2 constructed and operated in accordance with the rack shown,
- described and claimed in my Patent No. 1,443,023, granted Jan. 23, 1923. A trumper head is designated generally at 3 and is belt driven in the ordinary way. In conjunction 60 with the press box a gate 4 is provided and is constructed, controlled and operated exactly as the gate 54 of my prior Patent No. 1,443,023, granted Jan. 23, 1923.
- The means for driving the trumper head 65 3 includes a driving shaft 5 on which an idle or loose pulley 6 and a shaft or fixed pulley 7 are mounted, the pulley 6 being free to rotate relative to the shaft but the shaft and pulley 7 being constrained to partake of corresponding rotary movement. A belt 8 is employed in conjunction with the pulleys 6 and 7 for driving the shaft 5. When the belt 8 is engaged with the pulley 6 its motion is not transmitted to the shaft 75 5 since the pulley 6 rotates on the shaft 5. When the belt 8 is engaged with the pulley 7 the shaft 5 is driven and consequently the 80 packer head 3 is caused to automatically descend and ascend in the press box. The motion transmission means between the shaft 5 and the trumper head is well known and widely employed and needs no detailed description here.
- The automatic attachment which constitutes the present invention comprises a belt shifter, designated generally at 9, and which co-acts with the belt 8 under the influence of the automatic attachment for causing the belt 8 to be engaged with the fixed pulley 7 90 when the press box has been filled with cotton and for shifting the belt back onto the loose pulley when the trumper head has completed a cycle of operation; that is, when it has descended to compress the cotton and then ascended up to the limit of its return stroke. In carrying out these purposes the automatic attachment comprises a carrier bar 10 on which the belt shifter 9 is fixed. The carrier bar 9 is mounted for free sliding or shifting movement in roller bearings 11. A shiftable control bar 12 is provided and is also slidably mounted in the roller bearings 11 parallel and adjacent to the carrier bar 10. At one end the bar 12 is provided with a laterally extending roller 13 which is co-operable with a cam 14 fixed to the trumper head 3. A latch 15 is pivoted, as at 16, to the control bar 12 and has a hooked and beveled end 17 engageable with a laterally extending stud 18 fixed to the carrier bar 10 and projecting toward the bar 12.

When the latch 15 has its hooked end 17 engaged with the stud 18, the bars 10 and 12 are held together. Consequently, when the trumper head 3 is at the upper limit of its stroke and the press box is being filled, both bars 10 and 12 are held in the position shown in Fig. 1, wherein the belt shifter 9 has shifted the belt 8 onto the loose pulley 6, whereby to permit the trumper head 3 to remain stationary. When the press box 3 has been filled by the action of the rake 2 with the desired amount of cotton, the gate 4 is swung outwardly. A crank arm 18 is fixed to the gate 4 and is connected by a link 19 to a crank arm 20 on one end of a shaft 21. The shaft 21 is journaled in bearings 22 and also carries a crank arm 23 connected by a connecting rod 24 with a latch release bar 25. The latch release bar 25 is fulcrumed, as at 26, on bearings 27 and this bar may also be counterweighted, as at 28. One end of the latch release bar 25 is engageable with the tail 15^a of the latch 15. With this arrangement when the cotton has filled the press box to such an extent as to swing the gate 4 outwardly around its hinges 4^a, the crank arm 18, link 19, crank arm 20, shaft 21, crank arm 23 and connecting rod 24 transmit the motion of the gate to the latch release bar 25. The latch release bar 25 presses down on the tail 15^a of the latch 15 to disengage the hooked end 17 of the latch from the stud 18. When the latch 15 has its hooked end disengaged from the stud 18 a retractile coil spring 30 operates to shift the carrier bar 10 to the right, as viewed in Fig. 1. This movement of the carrier bar 10 shifts the belt shifter 9 to the right and consequently shifts the belt 8 from the fixed pulley 7 to the loose pulley 6 and starts the trumper head 3 on its down stroke. As the trumper head 3 moves downwardly, the cam 14 disengages the roller 13 and permits the control bar 12 to shift to the right, as viewed in Fig. 1, causing the beveled end of the latch 15 to snap over the stud 18 so as to again connect the bars 10 and 12. At this time the latch release bar 25 is also repositioned due to the fact that the cotton is carried down past the gate 4 by the trumper head. On the return stroke of the trumper head the cam 14 again engages the roller 13 and consequently shifts the bar 12 to the left, as viewed in Fig. 1. Since the bar 10 is connected to the bar 12 through the latch 15 and stud 18 it is also shifted to the left as viewed in Fig. 1 and as a consequence the belt shifter 9 shifts the belt 8 from the fixed pulley 7 to the loose pulley 6 to stop the movement of the trumper head.

Braking mechanism is provided for immediately stopping the motion of the fixed pulley 7 and the shaft 5 when the belt 8 is disengaged from these bars. Preferably this braking mechanism includes a pivoted

brake beam 35 having one end pivotally mounted, as at 36, on a stud shaft 37 carried on the stationary part of the structure. The brake proper consists of a laterally extending and suitably faced braking element 38 carried by the brake beam 35 and engageable with the periphery of the fixed pulley 7 between the runs of the belt 8. A brake operating arm 39 is fixed to the carrier bar 10 and has an eye 40 through which a brake rod 41 is slidably fitted. A spring take-up 42 is provided between the eye 40 and one end of the rod 41. The other end of the rod 41 is pivotally connected, as at 43, to one arm of a bell crank 14. The other arm of the bell crank is connected by a twisted link 45 to one end of the brake beam 35. With this arrangement when the bar 10 shifts to the right, as viewed in Fig. 1, to shift the belt 8 onto the fixed pulley, the brake arm 35 also shifts to the right and releases the brake. When, however, the bar 10 is shifted to the left, as viewed in Fig. 1, to draw the belt 8 onto the loose pulley, the brake arm 39 will also move to the left as viewed in Fig. 1, and this will cause a corresponding movement of the rod 41 and a swinging movement of the bell crank 44 about its pivot in a clockwise direction, as viewed in Fig. 1, thereby exerting a pull on the link 45 and swinging the brake beam 35 to pull the braking element 38 into engagement with the periphery of the pulley 7.

I claim:

1. In a belt driven cotton packer having a press box, a trumper, means for feeding cotton to the press box, and means for driving the trumper including a shaft, a loose pulley on the shaft, a fixed pulley on the shaft, a belt co-operable with the pulleys, an automatic attachment for the packer including a shiftable carrier bar having a belt shifter co-operable with said belt, a control bar, a releasable self-setting connection between the control bar and the carrier bar, means controlled by the amount of cotton in the press box for releasing the connection between the control bar and the carrier bar, means for biasing the position of the carrier bar to cause the belt shifter to shift the belt onto the fixed pulley, and means on the trumper and co-operable with the control bar for shifting the control bar so as to cause it to shift the carrier bar to throw the belt onto the loose pulley when the bars are connected and the trumper is at the upper limit of its stroke.

2. In a belt driven packer, an automatic attachment including a pair of bars, a belt shifter carried by one bar, a latch and stud arrangement for connecting the bars, means controlled by the amount of cotton in the press box for disconnecting the latch from the stud, means for shifting one of the bars when the latch and stud are disconnected,

and tramper control means for shifting the other bar.

3. In a belt driven cotton packer including a press box, a tramper, means for driving the tramper including a shaft having a fixed pulley and a loose pulley thereon, a gate associated with the press box and swingable outwardly from the press box when the press box is filled with cotton, an automatic attachment including a slidable carrier bar, a belt shifter connected to the carrier bar, a slidable control bar, a latch pivoted on the control bar, a stud on the carrier bar engageable with the latch, springs for biasing the position of said bars, a latch release bar co-operable with the latch, motion transmission means between the gate and the latch release bar, a roller on the control bar, and a cam on the tramper head co-operable with the roller.

4. In a belt driven packer, an automatic attachment including a pair of bars, a belt shifter carried by one bar, releasable means for connecting the bars, means controlled by

the amount of cotton in the press box for 25 releasing said means, means for shifting one of the bars upon release of said releasable means, and tramper control means for regulating the shifting of the other bar.

5. An automatic attachment for belt 30 driven packers comprising a shaft, a loose pulley on the shaft, a fixed pulley on the shaft, a belt co-operable with the pulleys, a shiftable carrier bar having a belt shifter 35 co-operable with said belt, a control bar, a releasable connection between the control bar and the carrier bar, means for automatically releasing said connection, means for biasing the position of the carrier bar to cause the belt shifter to shift the belt from 40 the loose pulley onto the fixed pulley, and means co-operable with the control bar for automatically shifting the control bar so as to cause it to shift the carrier bar in such manner that the belt will be moved onto the 45 loose pulley when the bars are connected.

WILKIE HORATIO HOLTBY.
